UNITED STATES PATENT OFFICE.

WILLIAM HERTZBERG, OF BROOKLYN, NEW YORK.

BROOM.

Application filed September 17, 1925. Serial No. 56,975.

This invention relates to improvements in brooms and an object thereof is the provision of a metallic broom-head which holds the broom-straw securely and which divides the broom into a plurality of sections.

A further object of the invention is to provide a broom which avoids the use of cord or similar perishable material in its construction.

With these and other objects in view the invention consists in the novel construction, combination and arrangements of parts to be hereinafter more fully described, and finally pointed out in the appended claim.

In the accompanying drawing, forming a material part of this disclosure:

Fig. 1 is a front elevation of a broom embodying the present invention, the right half of the front cover plate is broken away to show the interior.

Fig. 2 is a side elevation of Fig. 1.

Fig. 3 is a sectional plan on line 3—3 of Fig. 1.

Fig. 4 is a detail showing the construction of the stop at the neck opening for the broomstick.

Fig. 5 is a sectional plan on line 5—5 of Fig. 4.

Referring to the drawing, 1 represents a broom-stick for the broom which is held in the broom-head shells 2 and 3. These shells are preferably stamped from sheet steel and shell 2 overlaps shell 3 at its outer edges at 2^a. The broom stick 1 enters the shells at the neck opening 4 and the broom material which is preferably piazzava or Bahia fiber, rice straw or a similar kind, enters the lower elongated opening formed by the shells and extends upward to the plane indicated by 6 on the drawing. The broomstick 1 preferably extends downward to the same plane. The faces of the two shells 2 and 3 are arranged to gradually come closer together from the neck 4 to the bottom opening 5, so that a tapering space is formed between them. To hold the shells the desired distance apart at the neck to form the proper opening for stick 1 shoulders 7 are formed by notching and bending both shells in such a manner that when joined the edges of plates at 8 lie in one circle and do not overlap at the opening, while the shoulders 7 hold the shells the required distance apart.

Both shells 2 and 3 are provided with rec-

tangular openings 10 near their lower end. Both horizontal edges of each plate at the openings are provided with teeth 11 spaced apart and opposite each other transversely in horizontal direction on either shell and 60 vertically on the same shell. These teeth are so long that their points almost touch each other and that they separate the broom-straw on vertical, transverse planes.

The reeds of the broom-straw are cemented 65 together from slightly above opening 10 to plane 6 by means of asphaltic cement, rubber or the like to form a solid compact mass. As the space between shells 2 and 3 increases upwardly, the body formed by 70 cementing the material together increases in thickness in the same direction and is prevented from moving downward in addition to the holding power of teeth 11 in 75 the same direction.

The two shells are held together, the broom-stick fastened thereto and the broom-straw clamped therein by means of a plurality of long tubular rivets or eyelets 12 which penetrate the broom-holder transversely and are spun over at either side to form heads. Two of these rivets 12^a penetrate the broomstick 1 and hold it securely against turning, swaying or pulling out. A series of rivets 12^b is arranged in a horizontal line to penetrate the cemented body of broom material about its central portion. These rivets are so placed that they are in staggered relation to the two horizontal rows of spaced teeth 11. In this manner each section of the broom, produced by the dividing action of teeth 11, is separately held by a rivet 12^b. Near the lower end 5 of the broom-holder, close to the corners of opening 10, two rivets 12^c hold the two shells together and divide the broom-straw into two somewhat smaller outside sections to give greater flexibility in sweeping action and a greater spread to the broom-straw at the bottom end of the broom.

The body of the broom consisting of the broom-straw cemented together, is preferably preformed in a mold ready for insertion into the shells. It is therefore an easy operation to replace a worn out broom with 105 a new one by removing the eyelet rivets, inserting a new body and reriveting.

From the above description taken in connection with the accompanying drawing, it 110 will be seen that I have provided a broom

which rigidly and securely holds the broom-straw and eliminates all binding strings without losing the desired effect of separating the broom into sections.

5 Binding strings break by deteriorating, the broom-straw falls out or breaks and the sweeping action is impaired or destroyed. The desired flexibility at the place where the strings are usually placed is attained
10 in my broom by the sheet metal bar above line 5 which produces just the desired flexibility at this place.

While I have shown and described the preferred form of my device as an example
15 of the many ways of practically constructing my improved broom it is understood that such changes may be made in its general arrangement, and in the construction of minor details thereof as come within the
20 scope of the invention defined in the claim,

without departure from the spirit of the invention and the principle involved.

Having thus described my invention what I claim as new and desire to secure by Letters Patent is:

25 In a broom, broom material, a pair of complementary metallic shells encasing the butt portions of said material, a series of lugs struck from the material of said shells at spaced distances from each other horizontally and vertically, and entering the broom material, and said series of lugs spacing said material to simulate tufts, and a separate fastening means passing through the base of each tuft and through both shells 30 above said spacing means.

35 In testimony whereof, I have signed my name to this specification this 15th day of September 1925.

WILLIAM HERTZBERG.
